UNITED STATES PATENT OFFICE.

HENRY E. CURTIS, OF SAN JOSE, CALIFORNIA, ASSIGNOR OF ONE-HALF TO JOHN H. BETTS, OF LONG BEACH, CALIFORNIA.

INTERNAL-COMBUSTION ENGINE.

Application filed May 5, 1927. Serial No. 129,083.

The present invention relates particularly to the piston head of an internal combustion engine and its relation to the combustion chamber of the engine.

- 5 It is the object of the present invention to provide a construction of the character indicated so formed and arranged as to positively effect more perfect combustion of the explosive mixture on compression.
- 10 It is also an object of the invention to provide a structure of the character indicated that will be simple in form and construction, economical to manufacture, and highly efficient in its practical application.

15 In the drawing:

Figure 1 is a vertical transverse section through a portion of an engine embodying my invention.

Figure 2 is a plan view of the portion of 20 an engine shown in Figure 1, part broken away.

Referring more particularly to the drawing, I show at 1 a portion of a cylinder block of an internal combustion engine with a 25 portion of a cylinder shown at 2. The combustion chamber is shown at 3 with a valve opening shown at 4 on a plane with the upper end of the cylinder 2. The head 5 encompasses the combustion chamber 3, a 30 portion of which is conical in form as shown at 6. The base of the conical portion 6 is preferably circular in form as at 7, and a portion of this circular part overlaps the cylinder 2 a distance as at 8 and, of course, in spaced relation thereto. The opening 9 35 is for the reception of a spark plug, not shown.

In the cylinder 2 is a piston 10 having its forward, or working, end 11 formed as 40 follows. That portion of the end of the piston operating directly under the conical portion 6 of the combustion chamber projects forwardly of the rest of the piston end as at 12 so that when the piston has 45 reached the limit of its compression stroke the part 12 extends into the conical portion of the combustion chamber. The inner surface of the part 12 slopes in an easy curve away therefrom as at 13 and is slightly 50 spaced from the edge 7 when the piston is in the said advanced position. This surface continues in a downward curve as at 14 until it approaches the sides of the piston whereupon it curves abruptly upwardly as 55 at 15, defining the inner side of the wall 16.

The wall 16 is in alignment with the outer surface of the piston and merges with the forwardly projecting portion 12 at 17 and 18, a distance from its extreme end.

When the engine is in operation the explosion occurs when the piston 10 is in the position shown. The burning gases, under the force of the explosion, pass through the narrow space 19 being directed downwardly and angularly by the flaring surface of the 60 conical portion 6 in conjunction with the sloping surface 13. These gases are constrained to move in the direction indicated by the arrows 20, passing over the surfaces 14 and 15 and then along the end wall 21 of 65 the combustion chamber. This movement of the burning gases is important, because in this manner the surfaces are all burned clean and remain clean of all carbon, the gases projected into the chamber above the 70 piston end burning from the outside toward the center instead of from the center toward the outside as is ordinarily the case.

The diffusion of the burning gases over the entire surface of the piston end and the 75 adjacent surface of the explosion chamber is rendered positive and complete by the narrow slot 19 existing at the time of the explosion and which directs the gases fanwise over the surfaces 14 and 15, thereby 80 creating a turbulence that effects a perfect 85 progressive burning of the mixture and effectually eliminates the "knocking" originating in the "spotty" burning of the mixture.

It is to be understood, of course, that 90 while I have herein shown and described but one specific embodiment of the invention, changes in form, construction, arrangement and method of operation may be made 95 within the scope of the appended claims.

I claim:

1. In an internal combustion engine, the combination of a cylinder, a piston therein having a curvilinear end surface cooperating with the opposing end of the cylinder to form a combustion chamber and a portion projecting forwardly of the piston, and an explosion chamber having a portion angularly overlying the projecting portion of 100 the piston and closely approaching the same at the extreme limit of its forward movement to form a restricted passage between the chambers.

2. In an internal combustion engine, the 110

combination of a cylinder, a piston therein having an end surface sloping inwardly from one side toward the other and cooperating with the opposing end of the cylinder to form a combustion chamber, and an explosion chamber having a surface formed thereon approaching the forward portion of the said piston surface to form a slot therebetween when the piston is at the end of its forward stroke.

3. In an internal combustion engine, the combination of a cylinder, a piston therein having an end surface sloping inwardly from one side toward the other and then outwardly a distance and cooperating with the opposing end of the cylinder to form a combustion chamber, and an explosion chamber having a surface formed thereon lying in part opposite the end of the piston and approaching the forward portion of its sloping surface to form a restricted passage therebetween when the piston is at the forward end of its stroke.

4. An internal combustion engine including a conical explosion chamber a cylinder communicating therewith and offset relative thereto, the explosion chamber being positioned forwardly of the cylinder and overlapping the same, and a piston in the cylinder having a portion of one end projecting forwardly a distance to extend into the explosion chamber at the limit of its compression stroke, the inner surface of the projecting part cooperating with the opposing sur-

face of the explosion chamber in said advanced position to form a restricted passage and curving backwardly toward the sides of the piston and thence abruptly forwardly to form the inner side of a forwardly projecting rim, the outer surface of the rim aligning with the outer surface of the piston, and the rim merging at both ends with the base of said forwardly projecting portion.

5. An internal combustion engine including an explosion chamber and a combustion chamber arranged in offset relation to each other both transversely and longitudinally, the combustion chamber being formed by one end of the engine piston and the opposing end of the cylinder in which the piston operates and the two chambers being connected at the time of each explosion by a restricted passage formed in part by the engine piston at the end of its compression stroke.

6. An internal combustion engine including an explosion chamber and a combustion chamber both laterally and longitudinally offset relative to each other but overlapping a distance, the combustion chamber being formed in part by the engine piston at the end of its compression stroke, and a restricted passage connecting the chambers at the time of each explosion and formed in part by the engine piston at the end of its compression stroke.

HENRY E. CURTIS.
